UNITED STATES PATENT OFFICE.

EZRA C. CARTER, OF JESUP, GEORGIA.

SHOT-SPLITTING MACHINE.

Application filed August 24, 1925. Serial No. 52,179.

This invention relates to improvements in machines for splitting buck shot for the manufacture of split shot sinkers, an object being to provide a machine in which the shot will be automatically fed to a splitting blade and discharged from the machine into a suitable receptacle or container.

Another object of the invention is the provision of a shot splitting machine which is simple and economical in construction, 10 easily operated and which will split a large number of shot in a relatively short time.

With the above and other objects in view, the invention further includes the following novel features and details of construction, to be hereinafter more fully described, illustrated in the accompanying drawings and pointed out in the appended claims.

In the drawings:—

20 Figure 1 is a side elevation of a shot splitting machine constructed in accordance with the invention.

Figure 2 is a fragmentary sectional view of the same.

25 Figures 3 and 4 are end views with the splitting blade in different positions.

Referring to the drawings in detail wherein like characters of reference denote corresponding parts, the reference character 30 10 indicates the base of the machine from which rise spaced standards 11, the latter being preferably of inverted U-shape as shown in Figures 3 and 4 of the drawings. Secured in the upper ends of these standards is a spacing sleeve 12 which also provides a bearing for a shaft 13, the said shaft carrying at one end an eccentric 14 and at its opposite end a fly wheel 15. The wheel may be provided with an operating handle 40 16 whereby the shaft may be rotated, or the shaft may be rotated by suitable source of power. For the latter purpose, the shaft has mounted thereon a grooved pulley 17.

Operating in spaced guides 18 carried by 45 one of the standards 11 is a slide 19 from the lower end of which extends a splitting blade 20. A pitman 21 has one of its ends pivotally secured to the upper end of the slide 19 as shown at 22 and its opposite end 50 pivotally secured to the eccentric 14 as shown at 23, so that rotation of the shaft 13 will reciprocate the splitting blade 20.

The blade 20 is designed to act upon a shot 24 which is located within a pocket or seat 55 25 provided immediately below the blade 20 and to split this shot in the manner illus-

trated in Figure 2 of the drawings. The pocket or seat is formed centrally of a bar 26 which extends across the lower end of the standard 11 and this bar is provided 60 with an upwardly extending lip or lug 27, the purpose of which will be later explained. Shot are fed singly into the pocket 25 through a feed chute 28 at the upper end of which there is located a hopper 29. The 65 shot feeds by gravity into the pocket 25 and is prevented from rolling beyond the pocket by the lip or lug 27 as will be clearly seen from Figure 2 of the drawings.

In the operation of the machine, the blade 70 20 in its downward movement will cut into the shot, reverse movement of the blade lifting the shot from the pocket due to friction between the blade and shot. In order to remove the shot from the blade there is provided 75 a spring arm 30 whose inner end is secured to the frame by the bolt or fastening devices 31 utilized to attach one end of the bar 26 and one end of the standard 11 to the base 10. The outer free end of the 80 resilient arm 30 is notched as at 32 to permit of the passage of the blade 20 so that the bifurcated end of the arm 30 is arranged in the path of upward movement of the shot so that the latter will be wiped from the 85 blade. An arm 33 which extends from the standard 11 acts to limit upward movement of the resilient arm. The shot moving upward with the blade 20 will engage the outer end of the arm 30 and the latter will move 90 upward a slight distance with the shot until the arm 30 engages the arm 33, whereupon, the shot will be wiped from the splitting blade and will be deflected into a trough 34 provided in the base 10, from which it may 95 roll into a bag or other suitable receptacle.

As the blade 20 is removable secured to the slide 19 as indicated at 35, this blade may be replaced when desired.

The invention is susceptible of various 100 changes in its form, proportions and minor details of construction and the right is herein reserved to make such changes as properly fall within the scope of the appended claims.

Having described the invention what is 105 claimed is:—

1. A shot splitting machine comprising a frame, a pocket designed to singly receive the shot to be split, means to feed the shot to the pocket, a splitting blade positioned 110 to act upon the shot within the pocket, means to actuate the blade to split the shot and

lift the latter from the pocket, a resilient arm having its outer end located in the path of movement of the split shot and means engageable with the resilient arm to limit 5 movement of said arm in one direction to wipe the shot from the blade.

2. A shot splitting machine comprising a frame, a shot feeding chute mounted thereon, a bar extending transversely across the 10 discharge end of the chute and provided with a pocket to singly receive the shot from the chute, a stop extending from one edge of the bar adjacent the pocket in the path of the shot and remote from the discharge end 15 of the chute, a splitting blade operable to split the shot and lift the latter above the stop and means located in the path of upward movement of the split shot to remove the latter from the blade.

3. A shot splitting machine comprising 20 a base, spaced standards rising from the base, a horizontally disposed shaft mounted for rotation in said standards, a vertically movable splitting blade mounted for sliding movement upon one of the standards, a bar 25 extending horizontally across the base at the lower end of one of the standards, a pocket included in the bar beneath the plate, means to feed the shot singly to the pocket to be acted upon by the blade, a stop carried by 30 the bar adjacent the pocket, means connecting the shaft and blade to reciprocate the latter and split the shot and lift said shot from the pocket and means to remove the shot from the blade. 35

In testimony whereof I affix my signature.

EZRA C. CARTER.
